BATTERY CLAMP TOOL

Frank H. Kopisch, Blackwell, Okla.

Application April 22, 1940, Serial No. 331,016

1 Claim. (Cl. 81—5.1)

This invention relates to battery clamp tools and has for an object to provide a tool which will spread and remove the clamp and which can be used either vertically or horizontally on right- or left-hand clamps.

A further object of the invention is to provide a tool which will securely hold one end of the bolt while a nipper edge securely holds and spreads the clamp without strain on the battery post.

Another object of the invention is to provide a tool which can be used any place or position that a battery terminal nut wrench or pliers can be used and which will be as easy to use as an ordinary pair of pliers.

A further object is to provide a device of this character which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming a part of this specification:

Figure 1 is a top plan view of a battery clamp tool constructed in accordance with the invention and shown in applied position.

Figure 2 is a fragmentary top plan view of the device also shown in applied position but disposed at an angle.

Figure 3 is a sectional view of one of the jaws taken on the line 3—3 of Figure 1 looking in the direction of the arrows.

Figure 4 is a sectional view of the other jaw taken on the line 4—4 of Figure 1 looking in the direction of the arrows.

Referring now to the drawing in which like characters of reference designate similar parts

in the various views, 10 designates a pair of pliers having a long jaw 11 and a short jaw 12.

The long jaw 11 is provided on its face 13 with three relatively spaced recesses 14 and the short jaw 12 is provided with three nipper edges 15. One of the recesses 14 is located in the longitudinal center of the face 13 of the jaw 11 and the remaining recesses 14 are located at opposite sides of said center. One of the nipper edges 15 is located at the forward end of the face 16 of the jaw 12, and the remaining nipper edges 15 are located at the lateral sides of the face 16 of the jaw 12 and the latter nipper projections, located on the flat side faces, extend in the direction of length of the tool and are curved at the tip to extend beyond the working face of the short jaw. The nipper edges 15 are arranged at an oblique angle with relation to the jaw 12, see Figure 5.

20 When the device is in use one of the recesses 14 receives the end of the bolt 17 of the battery clamp 18 and the corresponding nipper edge 15 contacts with the inner face of one end of the battery clamp 18. The arrangement of the recesses 14 and nipper edges 15 is such as to permit the device to be used vertically or horizontally and also in connection with battery clamps of either right- or left-hand style.

From the above description it is thought that the construction and operation of the invention will be fully understood without further explanation.

What is claimed is:

A battery clamp tool comprising a pair of pliers having cooperating long and short jaws, the short jaw having flat side faces, a nipper projection on one of the flat side faces extending in the direction of length of the tool and curved at the tip to extend beyond the working face of the short jaw, the long jaw having a recess in the working face adapted to receive the clamp bolt of a battery clamp when said nipper projection is inserted between the ends of the battery clamp.

FRANK H. KOPISCH.
